DESIGN FOR A SIGN OR SIMILAR ARTICLE

Joseph K. Franks, Morristown, N. J.

Application November 30, 1940, Serial No. 96,969

Term of patent 3½ years

To all whom it may concern:

Be it known that I, Joseph K. Franks, a citizen of the United States, residing at Morristown, in the county of Morris and State of New Jersey, have invented a new, original, and ornamental Design for a Sign or Similar Article, of which the following is a specification, reference being had to the accompanying drawing, forming part thereof.

The figure is a perspective view of a sign or similar article embodying my new design.

The side opposite the side shown in the drawing is plain.

I claim:

The ornamental design for a sign or similar article, as shown and described.

JOSEPH K. FRANKS.
